COMBINED KITCHEN FAUCET AND HANDLE

Donald M. Genaro, Haworth, N.J., and Charles W. Pelly,
Scarsdale, N.Y., assignors to American Standard Inc.,
New York, N.Y.

Filed Mar. 6, 1972, Ser. No. 232,356

Term of patent 14 years

Int. Cl. D23—01

U.S. Cl. D23—23

FIG. 1

FIG. 2

FIG. 3

FIG. 4

FIG. 1 is a perspective view of a combined kitchen faucet and handle embodying my new design;

FIG. 2 is a front elevational view thereof;

FIG. 3 is a left side elevational view thereof; and
FIG. 4 is a right side elevational view thereof.

I claim:

The ornamental design for a combined kitchen faucet and handle, substantially as shown.
